[57] **CLAIM**

The ornamental design for an end cap for a baseball or softball bat, as shown and described.

DESCRIPTION

FIG. 1 is a front elevational view of an end cap for a baseball or softball bat which embodies my design;

FIG. 2 is a left side isometric view thereof;

FIG. 3 is a rear elevational view thereof; and,

FIG. 4 is a left side elevational view thereof, the undisclosed sides being identical.

The broken line showing is for illustrative purposes only and forms no part of the claimed design.
